(57) **CLAIM**

We claim the ornamental design for a substrate shipper component, as shown.

DESCRIPTION

FIG. 1 is a back perspective view of a substrate shipper component, according to the invention.

FIG. 2 is a front perspective view of a substrate shipper component, according to the invention.

FIG. 3 is a top plan view of a substrate shipper component, according to the invention.

FIG. 4 is a side elevational view of a substrate shipper component, according to the invention.

FIG. 5 is a side elevational view of a substrate shipper component, according to the invention; and,

FIG. 6 is a top perspective view of a substrate shipper component, according to the present invention.

The broken lines in the drawing depict environmental subject matter only and form no part of the claimed design.
